UNITED STATES PATENT OFFICE

JAMES N. SIME, OF CHICAGO, ILLINOIS

HOSE SUPPORTER

Application filed May 4, 1931. Serial No. 534,846.

This invention relates to hose supporters and one of the objects of the invention is the provision of a new and improved garter having novel means for compensating for the difference in circumference of the parts around which the garter is secured when in use.

A further object of the invention is the provision of a new and improved fabric adapted especially for use as garter material, that is provided with elastic warp strands that are so constructed and arranged that the lower edge of the garter will stretch more easily than the upper portion thereof.

A still further object of the invention is the provision of a new and improved garter that is inexpensive to manufacture, easily assembled and that is form fitting and comfortable to the wearer during its use.

Other and further objects of advantages of the invention will appear from the following description taken in connection with the accompanying drawing, in which

Fig. 1 is an elevation of a portion of the improved fabric;

Fig. 2 is a section on line 2—2 of Fig. 1;

Fig. 3 is a side elevation of a garter made from the improved fabric, showing its position in use, with the leg of the user shown in dotted lines and Fig. 4 is a vertical section of a modified form of the fabric construction.

It is common practice in the manufacture of fabrics for men's garters to incorporate warp strands of rubber of uniform cross-sectional area throughout the width of the fabric, said strands extending longitudinally of the garter. Such an arrangement is objectionable because in use the lower edge of the garter will be stretched more than the upper portion in order to conform to the shape of the leg, and if tight enough at the top will be too tight at the lower edge.

The present invention seeks to remedy this defect by the provision of a garter made from a fabric in which the warp strands of rubber or other elastic material increase in cross-section from the lower edge toward the upper edge of the garter, whereby when in use pres-

sure of the garter on the leg will be the same throughout its width.

Referring now to the drawing, the reference character 10 designates the fabric from which the garter 11 is made. As shown, in Figs. 1 and 2, strands of rubber 12 are employed in the warp of the fabric. These strands may gradually increase in cross-sectional area from what will be termed the lower edge of the fabric 13 toward the upper edge 14 thereof.

In Fig. 3 is disclosed the conventional form of garter shown as extending about the leg 15 and comprising the usual detachable fastener 16 and 17, the supporting member 18, the hose attaching member 19 and 21 including the button 22 and the adjusting clip 23. Since the details of this portion of the garter constitute no part of the present invention it is not thought necessary to further illustrate or describe the same. From an inspection of this figure it will be seen that the lower edge 13 of the garter engages the calf 24 of the leg and consequently the lower edge must necessarily be stretched more than the upper edge thereof.

In the construction shown in Fig. 4 the elastic warp strands 25 are separated farther apart at the lower edge 26 of the fabric than they are toward the upper edge 27 thereof. Preferably the space between the strands 25 gradually decreases from the lower to the upper edge of the fabric as shown in this figure. By means of this arrangement the lower edge of the fabric when used as a garter would be more easily stretched or extended than the upper portion thereof, and since the force required for extending any one of the bands a given distance will increase as the band is extended, all parts of the garter will bind on the leg of the user with equal force. In this form of construction the strands 25 are of the same cross-sectional area throughout the entire width of the fabric.

In all cases, the fabric is so constructed that the portion that is to extend about the larger circumference is more easily initially stretched than the remainder so that the tension will be about equal on all parts of the fabric when it is in position for use. This may be accomplished in various ways, as by

using elastic warp strands of the same cross-sectional area and unevenly spacing the strands apart, or by using strands of varying elasticity, or by varying the cross-sectional area of the elastic strands, but under all circumstances the ultimate object of the invention is to equalize the pressure on the parts throughout the width of the fabric, while the same is in use.

I claim as my invention:

10. 1. A garter comprising an elastic band, a clasp for connecting the ends of said band together, a hose supporting member extending downwardly from said band, hose attaching members on the lower end of said supporting member, said band comprising a fabric having warp strands of rubber of progressively increasing cross-sectional area from its lower edge toward its upper portion, the edges of said garter being of substantially the same length when the same is not in use.
15. 2. A garter comprising an elastic band, a clasp for connecting the ends of said band together, a hose supporting member extending downwardly from said band, hose attaching members on the lower end of said supporting member, said band comprising a fabric band having elastic warp strands extending throughout its width, said strands progressively increasing in strength from the lower edge of said band toward its upper edge with the uppermost elastic strands of a cross-sectional area greater than those of the lower strands, all of said strands being of substantially the same length and unextended when said garter is not in use.

In testimony whereof I affix my signature.
JAMES N. SIME.
